UNITED STATES PATENT OFFICE.

KALMER UELAND, OF SHELLY, MINNESOTA.

BELT-THROWING DEVICE.

No. 837,982.

Specification of Letters Patent.

Patented Dec. 11, 1906.

Application filed June 4, 1906. Serial No. 320,090.

To all whom it may concern:

Be it known that I, KALMER UELAND, a citizen of the United States, residing at Shelly, in the county of Norman and State of Minnesota, have invented certain new and useful Improvements in Belt-Throwing Devices; and I do hereby declare the following to be a full, clear, and exact description of the invention, such as will enable others skilled in the art to which it appertains to make and use the same.

My invention has for its object to provide an improved belt-throwing device especially adapted for use in connection with threshing-machine engines; and to the above ends the invention consists of the novel devices and combinations of devices hereinafter described, and defined in the claims.

The invention is illustrated in the accompanying drawings, wherein like characters indicate like parts throughout the several views.

Referring to the drawings, Figure 1 is a plan view showing the improved belt-throwing device. Fig. 2 is a horizontal section taken through the device on the line $x^2 x^2$ of Fig. 3. Fig. 3 is a vertical section taken approximately on the line $x^3 x^3$ of Fig. 1, and Fig. 4 is a side elevation of the said device.

The numeral 1 indicates a supporting bracket, which, as shown, is provided with a hollow horizontally-projected stem portion 2, that is rectangular in cross-section. The said bracket 1 is adapted to be secured to the boiler of the engine adjacent to the driving-pulley thereof. A rectangular sleeve 3 is mounted to slide on the hollow stem portion 2, and this sleeve is provided with a vertical spindle 4, upon which is loosely mounted a vertically-disposed guide-roller 5.

The outer end of the hollow stem 2 is bifurcated, and a head 6 is pivoted thereto, as shown, by means of a bolt 7. This head 6 carries a spindle 8, upon which a guide-roller 9 is loosely mounted. The head 6 is normally held, as shown in Fig. 3, by means of a lock-dog 10, that is pivoted within the hollow stem 2 by a pin 10^a and engages a tooth or shoulder 11 on the said head 6. When the roller 9 is held in the position shown in Fig. 3, the two rollers 5 and 9 are in position to guide the belt 12 to the pulley, (not shown,) but over which the said belt will in practice be arranged to run.

As a means for causing the sleeve 3 to move upon the stem 2 a bell-crank 13 is pivoted at

14 to the bracket 1, and one arm of this bell-crank is connected to said sleeve by a link 15, while the other arm of said bell-crank is connected by a long link 16 to an operating-lever 17, which latter may be pivotally mounted on any suitable part of the engine.

The lock-dog 10 before noted is provided with a long arm 10^b , that extends horizontally within the hollow stem 2 and normally rests upon one arm of a small bell-crank 18, which bell-crank is pivotally supported within said stem 2 by a transverse pin 19 and the other arm of which projects upward. The sleeve 3 carries a tripping-plate 20, which, as shown, is directly secured to the depending end of the spindle 4. It will be noted that the top of the hollow stem 2 is slotted at 2^a to afford clearance for the hub portion of the tripping-plate 20. The upwardly-projecting arm of the bell-crank 18 normally rests against the outward extremity of the said tripping-plate 20, but stands in such position as to permit the dog 10 to engage the tooth 11 of the pivoted roller-supporting head 6.

When it is desired to quickly throw the belt off from the engine-pulley over which it normally runs, the said belt is forced outward and out of line with said pulley by an outward movement of the guide-roller 5. This outward movement of said pulley 5 is accomplished by a movement of the lever 17 toward the right from the position shown, under which movement the sleeve 3, together with said guide-pulley 5, are moved outward. The initial outward movement of the sleeve 3 causes the tripping-plate 20 to force the upper arm of the bell-crank 18 toward the right with respect to Fig. 3 and then slightly downward, thereby raising the other arm of said bell-crank and the long arm 10^b of the lock-dog 10, and thereby causing said lock-dog to release the pivoted head 6, so that the roller 9 when pressed outward by the engagement of the belt 12 therewith will be caused to drop into the position shown in Fig. 4. It will thus be seen that the outward movement of the roller 5 positively crowds the belt off from its pulley and that the roller 9 is automatically dropped into an inoperative position, so that it will not prevent the said belt from being readily thrown off from said pulley.

The device above described while simple and of small cost affords means for very quickly and easily throwing a belt from its coöperating pulleys, and, furthermore, when

the rollers of the said device are held in their operative positions they afford a belt-guide for preventing the belt from being accidentally run off from the coöperating pulleys.

5 I claim as my invention—

1. In a belt-throwing device, the combination with a supporting-bracket, of a pair of roller-supporting devices, one of which is mounted to slide upon said bracket and the other of which is directly pivoted thereto, rollers mounted on said roller-supporting devices, a lock for normally holding the pivoted roller-supporting device in operative position, means for moving said sliding roller-supporting device, and means for causing said lock to release said pivoted roller-supporting device, when the said sliding roller-supporting device and coöperating roller are moved laterally, substantially as described.
- 15 2. In a belt-throwing device, the combination with a supporting-stem and a sleeve mounted to slide thereon, of a belt-guiding roller carried by said sleeve, a head pivoted to the outer head of said stem, a roller mounted on said head, a lock-dog operative on said head to hold the roller supported thereby in an operative position, means for sliding said

sleeve on said stem, and a device carried by said sleeve for causing said dog to release 30 said head under a sliding movement of said sleeve, substantially as described.

3. In a belt-throwing device, the combination with a hollow stem and a sleeve mounted to slide thereon, of means for moving said sleeve on said stem, a belt-guiding roller carried by said sleeve, a head pivoted to the outer end of said stem, a belt-guiding roller supported by said head, a lock-dog operative on said head to normally hold the roller carried thereby in an operative position, said lock-dog having an arm extending within said sleeve, a tripping bell-crank mounted within said stem and operative on the arm of said lock-dog, and a tripping-plate carried by 45 said sleeve and operative on said tripping bell-crank to cause the same to trip said lock-dog, under sliding movement of said sleeve, substantially as described.

In testimony whereof I affix my signature 50 in presence of two witnesses.

KALMER UELAND.
